(57) CLAIM

We claim the ornamental design for a bed, as shown and described.

DESCRIPTION

FIG. 1 is a front perspective view of a bed according to the invention. The view from the adjacent front corner being a mirror image thereto.

FIG. 2 is an elevational view of a the headboard of the bed according to the invention.

FIG. 3 is a side elevational view of the headboard of the bed according to the invention. The view from the opposite side being a mirror image thereto.

FIG. 4 is a plan view of a bed according to the invention.

FIG. 5 is a front elevational view of the footboard of a bed according to the invention; and,

FIG. 6 is a side elevational view of a footboard of a bed according to the invention.

The headboard and footboard are shown separately for clarity of disclosure.

The view from the opposite side being a mirror image thereto. The broken lines on the bed in the figures are for illustrative purposes only and form no part of the claimed invention. The backside of the footboard and the headboard of the bed are not shown and form no part of the claimed invention.

1 Claim, 4 Drawing Sheets
